UNITED STATES PATENT OFFICE.

WALLACE B. HUGHES, OF DALLAS, TEXAS, ASSIGNOR OF ONE-THIRD TO
JOE SAMUELS, OF DALLAS, TEXAS.

WIRE FENCE.

SPECIFICATION forming part of Letters Patent No. 757,928, dated April 19, 1904.

Application filed July 23, 1903. Serial No. 166,718. (No model.)

To all whom it may concern:

Be it known that I, WALLACE B. HUGHES, a citizen of the United States, and a resident of Dallas, in the county of Dallas and State of 5 Texas, have made certain new and useful Improvements in Wire Fences, of which the following is a specification.

My invention is an improvement in wire fences, and particularly in that class of such 10 fences which employ line-wires composed of strands twisted together to form a twisted cable, and the invention relates particularly to the connection between the fence-stays and the cables; and the invention consists in certain 15 novel constructions and combinations of parts, as will be hereinafter described and claimed.

In the drawings, Figure 1 is an elevation of a portion of a fence embodying my invention. 20 Fig. 2 is a perspective view of a portion of the fence, showing parts of two cables and a completed joint between the stay-sections and the cable and also portions of two stay-sections applied to the cable in position to be 25 twisted into connection therewith. Fig. 3 is a perspective view of one of the joints between the cable and the stay-sections with the latter given what may be termed their "initial" bend. Fig. 4 is a perspective view of one of 30 the joints with the stay-sections given additional twists to the bends shown in Fig. 3. Fig. 5 is a detail perspective view showing one of the joints between the cables and the stay-sections complete, and Fig. 6 is a cross-section on about line 6 6 of Fig. 1.

In carrying out my invention I provide line-wires in the form of cables A, each consisting of two strands *a*, twisted together, as shown in the drawings. For convenience in manufacturing it is preferred to twist the strands *a* in reverse directions in the adjoining meshes of the fence or, rather, between the adjacent stays, as will be understood from Fig. 1; but I do not desire to be limited in the broad features of my invention to this reversing of the twist.

An important feature of my invention is the construction of the fence with line-wires composed of twisted cables and with the stays

formed of sections whose meeting ends are 50 passed between the strands *a* of the cable and then secured. In other words, an important feature of my invention is the construction of a fence with twisted cables and stays made in sections with their meeting ends passing between the strands of the cable. This is well 55 illustrated in Fig. 2 of the drawings in which the upper and lower stay-sections B and B' have their meeting ends *b* and *b'* passed between the strands *a* of the twisted cable A ready to be 60 twisted around their respective strands *a*, as illustrated in Figs. 3, 4, and 5 of the drawings. If now the meeting ends *b* and *b'* of the sections B and B' be bent in the direction indicated by the arrows in Fig. 2, they will be brought first to 65 the position shown in Fig. 3. A further movement of the ends *b* and *b'* in the direction of the arrows in Figs. 2 and 3 will bring the ends *b* and *b'* to the position shown in Fig. 4. In continuing the twist of the ends *b* and *b'* 70 from the position shown in Fig. 3 to that shown in Fig. 4 it will be noticed that each end *b* and *b'* has been twisted entirely around its respective strand *a*, completely encircling 75 said strand *a*, as will be understood from Figs. 4 and 6 of the drawings. By this means I get a positive tie of the meeting ends of the stay-sections to their respective strands of the cable before the ends *b* and *b'* have been given the final twist around the body of the cable 80 to bring them to the completed position. (Shown in Fig. 5 of the drawings.) This is important in the construction of the complete fence, as by passing the meeting ends between the strands of the twisted cable and 85 twisting them in reverse directions around their respective strands of the cable I secure the stay-wires in a line with the center of the fence, so that the fence cannot be unrolled or pulled apart by a lengthwise strain on the 90 stay-wires. It will be understood from this that the twist in the ends of the stay-wire sections around the strands of the cable cannot be unrolled, nor can the fence be unrolled or pulled apart at the joints between the stay-sections and the cables by the strain of use 95 without breaking some of the wires, so that I am able to utilize all of the strength of all

- of the wires in the fence and make the strongest fence possible with the given size of wire. Further, an important advantage results from twisting the meeting ends of the stay-sections 5 first around their respective strands *a* and then around the body of the twisted cable, in that the stay-sections are locked from movement along the cables and only a small portion of the surfaces of the cables are pressed 10 upon by the stay-sections, so that the tendency to weaken the cables and to remove the galvanizing therefrom is greatly reduced.
- It will be noticed from Figs. 3, 4, and 5 that when the stay-sections are passed at their 15 meeting ends between the strands of the twisted cable while they are adjacent to each other they are free from any interlocking connection or hooking together in advance of being twisted around their respective strands 20 and thence around the twisted cable. This is important for several reasons. In the first place it avoids spreading the strands of the cable apart at the point where the stay-sections connect therewith, except to the extent 25 of the thickness of one of the said stay-sections. It also permits the ends of the stay-sections after being twisted first around their respective strands of the cable to rest close to the body of the stay-section from which such 30 particular end extends, so that the coils of the stay-sections around the strands rest close at one end against the stay-sections and may be brought into very compact form in the completed fence.
- 35 When the meeting ends of the stay-sections are brought to the final position, as shown in Fig. 5, they terminate one at the upper side of the cable, as shown in Fig. 5, and the other at the lower side of the cable, so that the 40 fence will present substantially the same appearance on both sides, and the extremities of the meeting ends of the stay-sections will be so disposed that they will not injure stock rubbing along either side of the fence.
- 45 It will be noticed from Fig. 3 that the meeting ends of the stay-sections are so directed in twisting them around the cables as to tighten the twist in the cables. To this end the ends *b* and *b'* are bent around the 50 cables in the direction of the twist of the

latter, thus increasing the tightness of the twist given to the cables.

It will be understood that in practice in the building of my fence by suitable machinery the stay-sections may be fed between the 55 strands *a*, as shown in Fig. 2, and then by suitable devices be twisted in the direction of the arrows in Figs. 2, 3, and 4 until the complete twist is formed, as shown in Fig. 5, the twisting of the strands *a* being continued 60 after the insertion of the stays to the position shown in Fig. 2, as will be understood from Figs. 3, 4, and 5 of the drawings.

Having thus described my invention, what I claim as new, and desire to secure by Letters 65 Patent, is—

1. The improved fence herein described consisting of the line-wires composed of strands twisted together to form a twisted cable, and stay-sections passed at their meeting ends in opposite directions between the strands of the twisted cable adjacent to each other, but free from interlocking connection and then twisted first entirely around their respective strands of the cable and then coiled 75 around the twisted cables substantially as and for the purposes set forth.

2. The combination in a fence substantially as herein described, of the line-wires composed of strands twisted together, forming a 80 twisted cable, and stay-sections inserted at their meeting ends between the strands of the twisted cable, with their ends extending in opposite directions through the cable, and free from interlocking connection with each 85 other, the said ends being then twisted first entirely around their respective strands and close against the side of the body of the section from which the respective ends extend, and then coiled around the twisted cable 90 whereby the spreading of the twisted cable at the point of insertion of the stay-sections is limited to the thickness of one of said sections and the coils may extend compactly from the stay-sections, substantially as and 95 for the purposes set forth.

WALLACE B. HUGHES.
